DESIGN FOR A LACE

Jean Dognin, New York, N. Y.

Application June 8, 1937, Serial No. 69,734

Term of patent 3½ years

To all whom it may concern:

Be it known that I, Jean Dognin, a citizen of the Republic of France, residing in city of New York, county of New York, State of New York, have invented a new, original, and ornamental Design for a Lace, of which the following is a specification, reference being had to the accompanying drawing, forming part thereof.

The figure is a plan view of a lace, showing my design.

The drawing shows substantially one-half the width of the lace, the upper half beginning with the upper horizontal dotted lines being the same but arranged in reverse order to complete the width of the lace.

I claim:

The ornamental design for a lace as shown and described.

JEAN DOGNIN.
